2 SHEETS—SHEET 2.

UNITED STATES PATENT OFFICE.

ROBERT C. DANLY, OF CHICAGO, ILLINOIS.

MAGNETO.

1,214,014.

Specification of Letters Patent. Patented Jan. 30, 1917.

Application filed April 3, 1914. Serial No. 829,235.

To all whom it may concern:

Be it known that I, ROBERT C. DANLY, a citizen of the United States, residing at Chicago, in the county of Cook and State of Illinois, have invented certain new and useful Improvements in Magnetos, of which the following is a specification.

My invention relates to electromagnetos for use in connection with internal combustion engines, wherein the charge of combustible fluid is ignited by means of an electric spark produced at recurring intervals by means of an electric current generated by a magneto deriving motion from a moving part 15 of the engine mechanism and suitably connected with the ignition mechanism.

The object of my invention is to provide a magneto simple in its construction, generating an electromotive force to produce 20 a strong current, and substantially proof against displacement of parts, and when once adjusted will continue to operate efficiently and positively for the purpose required. These objects are attained by means 25 of the mechanism illustrated in the accompanying drawings, in which—

Figure 1 is an end elevation of a magneto having my invention embodied in its construction; Fig. 2 is a partial bottom view 30 of Fig. 1; Fig. 3 is a vertical, longitudinal cross section of Fig. 1; Fig. 4 is a plan view of the armature; Fig. 5 is an end elevation of Fig. 4; and Fig. 6 is a view in perspective of one of the poles of the magneto.

Referring to the drawings, wherein the same reference numerals designate like parts throughout the several views, 1 represents a substantially rectangular case adapted to carry the operative parts of the mechanism, 35 and including top and bottom walls 2 and 3, respectively, an end wall 4, having integral therewith a centrally disposed journal box 5, and 6 represents oppositely disposed arms integral with the case and provided with 40 laterally disposed studs 7 arranged in the same horizontal plane as the axis of the journal box 5.

8 represents a removable end wall for the opposite end of the case, and integral therewith is a journal box 9 disposed in axial alinement with the journal box 5, at the opposite end of the case.

10 represents the poles of the magnets, and they form the side walls of the case 1 45 and are made integral therewith by being placed within the mold in the casting of the

case and having the molten metal, preferably brass, poured around them in a manner to rigidly connect them with the body of the case, the pole members being provided with 60 longitudinally disposed grooves 11 upon their opposite edges that receive a part of the metal of the body of the case in a manner to securely connect the poles therewith in an interlocking manner.

12 represents a permanent built up field magnet, preferably of the horse shoe form, having its poles securely connected with the poles 10 and side walls of the case 1 by being received between laterally extending rib 70 members 13 at opposite ends of the case that terminate at their upper ends in lip members 14 that are swaged closely against the edges of the bars of the magnets in the assemblage of the parts of the mechanism, and 15 represents a band of flexible material that is bent around the upper end of the magnet and secured to opposite sides of the base of the case 1 by means of screws 16.

The pole members 10 of the field magnet 80 12 are accurately finished upon their semi-circular faces, and 17 represents a rotatable armature including a core 18, comprising a series of separate plates of H-form of magnetic material, having axial openings therein 85 that receive the armature shaft 19, the plates being keyed to the shaft and 20 represents spacing blocks at opposite ends of the armature of non-magnetic material arranged at right angles with the body of the core, and 90 longitudinally disposed spacing bars 21 of similar material connected with opposite ends of the blocks 20 and secured thereto by means of rivets 22. The H-shaped plates are clamped together at their opposite ends 95 by means of sector heads 23 of non-magnetic material at opposite ends of the armature and through rivets 24. The cross heads 20 and bars 21 divide the space between the heads of the H-shaped core into two oppositely disposed longitudinal channels that receive armature coil windings 25 of insulated conductor wire, the coils being arranged parallel with the axis of the shaft 19, one end of the wire being secured to the 100 bottom of one of the channels of the core by means of solder, and after that channel has been nearly filled with wrappings the conductor is passed across and wound into the opposite channel, with the same number 110 of wrappings, and the end of the wire is secured to the free end of a clip member 26;

the opposite end of the clip being secured to an insulator disk 27 mounted upon the armature shaft 19, and having openings that receive the extended ends of the rivets 24, 5 the lower set of rivets 24 extending beyond the disk for a purpose to be described hereafter.

28 represents a plate upon the opposite side of the insulator disk 27 parallel with 10 the clip 26, and the two members are secured to the disk by means of rivets 29.

30 represents a coil of resilient conductor wire surrounding the shaft 19 at a distance therefrom, having one end connected with 15 one of the rivets 29 and its opposite end to the inner slotted end of a binding post 31 by means of a clamping screw 32. The binding post 31 includes a body portion 33 that is received by an opening in a boss 34 upon 20 the upper wall of the case 1 and insulated from the boss by means of a sleeve 35, a collar 36 near its upper end, a threaded lower end that receives a nut 37, and 38 and 39 represent insulating washers upon the out- 25 side and inside of the boss on the case, respectively, the washer 38 having one side flattened and engaging with the boss in a manner to secure it against rotation, as shown in Fig. 3. The upper end of the post 30 is cylindrical above the collar 36 and receives a coiled compression spring 40 and a pair of wire clamping disks 41 that are secured upon the post by means of a split ring 42 that is partially received by an annular 35 groove upon the upper end of the post, and 43 represents a conductor received between the disks and that may lead to the ignition mechanism of an engine; the spring 40 operating to automatically hold the disks in 40 engagement with the conductor. Secured to one end of the armature shaft 19, adjacent the bearing box 5, by means of a nut 44 and key 45, is a rocking arm 46, having a slotted opening 47 that may receive a recip- 45 roating rod whereby the magneto may be operatively connected with the ignition mechanism of an engine. The opposite end of the armature shaft 19 is journaled in the bearing box 9 in the end wall 8, that is se- 50 cured in position by screw studs 48, and when the parts are finally adjusted a seal 49 is placed upon one of the screws to insure that the inclosed parts of the mechanism will not be secretly or privately tam- 55 pered with.

Lubricant is supplied to the bearing 9 through the conduit 50, and a drip opening 51 is provided in the wall 8, below the journal, to carry away any surplus that might 60 otherwise be carried into the interior of the case and destroy a proper insulation of the parts. Integral with the arm 46 are oppositely disposed arms 52, at right angles with the axis of the shaft 19, and provided with 65 open ended slots 53 that receive sleeve mem-

bers 54, that are journaled upon pins 55 that are secured to the arms by means of washers 56, and split rings 57 received by annular grooves in the extended ends of the pins. The sleeves 54 are provided with annular grooves that receive the inner ends of coiled tension springs 58, the opposite end of the springs being connected in the same manner with like sleeve members 59 carried by the studs 7 at the ends of the arms 6.

The magneto is one of the oscillating type and is designed to be secured to an engine by means of screws received by threaded openings 60 in the base of the case 1, motion being imparted in one direction to the 70 armature against the force of the springs 58 by means of a reciprocating rod 61 that engages with the free end of the arm 46, the rod being actuated by a moving part of the engine properly timed with the movement 75 of the piston and ignition mechanism in any preferred manner, and the springs 58 oscillate the armature rapidly in an opposite direction inducing an electromotive force therein. The coil 30 takes the place of a 80 brush and winds and unwinds as the armature oscillates, and is subject to no disarrangement that would break or impair the current, and an accidental turning of the armature beyond the limits of its actuating 85 movement in either direction is prevented by the binding post 31 contacting with the extended ends of the rivets 24.

What I claim as being my invention, and desire to secure by Letters Patent, is:

1. A magneto including, in combination, a casing having top and bottom and one end wall comprising a one-piece structure, a second separable end wall, an armature journaled in said end wall, laterally extending 105 vertically disposed ribs at opposite ends of said case, said ribs having swaging elements at their opposite ends, pole pieces disposed upon opposite sides of the axis of said armature, said pole pieces being cast as one 110 piece with said case in a manner to form the side walls thereof and provided with longitudinally disposed interlocking elements along their opposite edges engaging with the top and bottom walls of said case in a 115 manner to rigidly secure said pole pieces in operative relation without other securing means, a field magnet having its pole received between said ribs and engaging with the outside faces of said pole pieces and having said swaging elements closed against the sides of said magnet in a manner to secure it in close contact with said pole pieces.

2. A magneto including, in combination, 120 a case, an oscillatory armature journaled in said case, an insulated binding post carried by said case, a coiled resilient current conductor having its opposite ends rigidly connected with said post and armature, respectively, and stop members carried by said 125 case.

armature and adapted to engage with said binding post in a manner to limit an oscillating movement of said armature in opposite directions.

5 3. In a magneto, a case, an oscillating armature journaled in said case, and including a laminated core piece, rivets securing the laminations in operative relation and ex-

tending beyond said core, a binding post carried by said case, said rivets contacting 10 with said post in a manner to limit a rotative movement of said armature.

ROBERT C. DANLY.
